UNITED STATES PATENT OFFICE.

WILLIAM S. HAMM, OF HUBBARD WOODS, AND THOMAS A. LEGGE AND NELS KROHN, OF CHICAGO, ILLINOIS, ASSIGNORS TO THE ADAMS & WESTLAKE COMPANY, OF CHICAGO, ILLINOIS, A CORPORATION OF ILLINOIS.

WASHSTAND.

1,226,879.

Specification of Letters Patent.

Patented May 22, 1917.

Application filed January 19, 1914. Serial No. 813,028.

To all whom it may concern:

Be it known that we, WILLIAM S. HAMM, a resident of Hubbard Woods, county of Cook, and State of Illinois, and THOMAS A. LEGGE and NELS KROHN, both residents of Chicago, county of Cook, and State of Illinois, and all citizens of the United States, have jointly invented certain new and useful Improvements in Washstands, of which the following is a specification, and which are illustrated in the accompanying drawings, forming a part thereof.

The invention relates to washstands such as are commonly used in sleeping cars; its object being to provide improved means for controlling the waste valve.

An embodiment of the invention is shown in the accompanying drawings, in which—

Figure 1 is a detail central vertical section 20 of a washstand showing the valve mechanism, the position of the waste valve when open being indicated in dotted lines; and

Fig. 2 is a sectional detail on the line 2—2 of Fig. 1.

The table of the washstand is represented at 10, and its bowl at 11. A waste pipe 12 leads from the bottom of the bowl, and is provided with an upwardly opening valve 13, the stem of which is pivoted at 14 within 30 a lateral recess of the waste pipe. A tube 15 leads from and substantially through the table 10 to the waste pipe 12, as shown, opening thereto through the recess within which the valve stem is pivoted.

A reciprocable flexible shaft 16 is housed within the tube 15, and is provided with a solid end 17 adapted to abut against a shoulder 18 formed on the stem 19 of the valve. The upper or outer end of the shaft 16 is 40 provided with a solid end 20, which is connected, by means of a link 21, with a hand lever 22 pivotally mounted within a cap 23 removably secured to the upper surface of the table 10, as by means of screws 24.

The shaft 16 is formed of a tightly wound wire coil which substantially fills the bore of the tube 15. The forward movement of the hand lever 22 from the position shown in Fig. 1 pushes the shaft through the tube 50 against the shoulder 18 of the valve stem, thereby raising the valve to the dotted lines position. The return movement of the lever 22 withdraws the shaft and permits the valve to close by gravity. The shaft may be 55 withdrawn from the tube by removing the

screws 24 and lifting the cap from its position on the table.

The shaft being a tightly wound coil, is non-compressible, and the pushing action upon the valve is therefore positive. Nevertheless, it is flexible so that it will adapt itself to a curved housing tube, whether this tube be curved to the form shown in the drawings or be bent in other directions, as frequently becomes necessary in properly locating the controlling lever upon the table.

An important feature of the invention is the provision of means for opening the valve with an upward and lateral movement, tending to move its stem to the side of the waste opening and to overturn the valve. By this action the waste port is opened practically to its full capacity; there is little chance for the accumulation of fibrous material, and the valve is accessible for repairs. This action is secured in the shown embodiment of the invention, by providing the valve with an L-shaped stem which is pivoted to the pipe connection at one side of the waste port.

We claim as our invention—

1. In combination, a wash bowl having a waste opening and pipe, a valve loosely seating downwardly in the opening, a curved arm pivoted within a lateral recess in the waste pipe, its free arm being pivotally attached to the valve, a shoulder on the end below its pivot for engagement by a push rod, a tube leading to the valve casing, and a coiled shaft reciprocable in the tube and having a plunger engageable with the shoulder.

2. In a washstand, in combination, a table, a bowl having a waste pipe, a valve seated in the receiving end of the pipe and openable upwardly, a lever pivoted in a lateral extension of the pipe and bearing upwardly on the valve and having a shoulder, a tube leading through the table to the lateral extension, a flexible shaft slidable in the tube and withdrawable therefrom and having engageable relation with the lever shoulder, a removable cap covering the upper end of the tube, a hand lever pivoted in the cap, and a link connecting the lever with the shaft.

WILLIAM S. HAMM.
THOMAS A. LEGGE.
